UNITED STATES PATENT OFFICE

JULIUS H. HERRMANN, OF PHILADELPHIA, PENNSYLVANIA

HANGER FOR FUR SCARFS OR THE LIKE

Application filed June 28, 1929. Serial No. 374,352.

My invention relates to hangers for fur scarfs or the like which are usually made up with the stuffed head of the animal at one end provided with a hook or tongue adjacent the head adapted to engage a loop at the other or tail end of the scarf when it is looped about the neck of the wearer while being worn.

Hitherto in the display or storage of such fur scarfs the practice has been to suspend them by tying a cord to some convenient part of the scarf, such as the head or tongue and attaching it to a hook or other support. This manner of suspending is unsatisfactory because the disengagement of the scarf for the purpose of exhibiting it to a customer or permitting it to be tried on is attended with considerable inconvenience, usually requiring the untying of the cord from the scarf, and also because the strings frequently break or become accidentally detached and allow the scarfs to fall on the floor. Furthermore the scarf as thus suspended does not lend itself to most appropriate display.

A principal object of my invention is to provide means for the suspension of fur scarfs for display and storage purposes whereby the scarfs are detachably secured at the head or snout end to a hanging device whereby the scarf may be maintained in full length, substantially vertical, suspension, thereby preventing distortion of the scarf and enabling a prospective customer to view it satisfactorily.

Another object of my invention is to provide a hanging device for fur scarfs having a securing means for the snout of the animal head which is adjustable for the varying lengths thereof and which forms a secure but easily removable attachment which may be readily attached to or removed from the scarf without injury thereto. A further object is to provide a hanging device for the purpose aforesaid which it is not necessary to disengage from the scarf when a customer wishes to examine or even try on the scarf, the hanger with the scarf being adapted for removal as a unit from the support for this purpose, and when so removed, not materially interfering with examination or temporary

use of the scarf while still attached thereto.

Additionally, my invention comprehends the combination of my improved hanger with a suspending means whereby a plurality of the hangers with the scarfs secured thereto may be hung therefrom and maintained in spaced, substantially vertical, positions upon the removal of one or more of the scarfs.

Other objects, advantages, and novel features will appear in the specification, accompanying drawing and the claims.

A full understanding of the invention may be obtained from a consideration of the detailed description of one embodiment thereof as shown in the accompanying drawing forming a part of this specification, it being understood, however, that while the drawing shows a practical form of the invention, the latter is not confined to strict conformity therewith, but may be changed or modified as desired so long as such changes or modifications embody no substantial departure from the salient features of the invention.

In the said drawing, Fig. 1 is a front view showing three fox skin scarfs suspended by means of my improved hangers, two being shown in dotted lines, and Fig. 2 is a side elevation, in part, thereof. Fig. 3 is a rear elevation, in part, of a fur scarf with my improved hanger in operative position thereon; Fig. 4 is an enlarged rear view of the hanger removed from the scarf; Fig. 5 is a section on the line 5—5 of Fig. 4 and Fig. 6 is a section on the line 6—6 thereof. Like numerals designate like parts in the several figures.

My improved hanger A comprises a frame 1 formed from wire, preferably of generally trapezoidal form and having elongated sides or legs 2 and 3 extending from the top 4 with the lower ends 5 and 6 of the wire bent inwardly substantially at right angles to form the base 7 and extending within a tubular member or spool 8 which is preferably adapted to rotate thereupon and which forms a protective cover for the free ends of the wire. I preferably hingeably attach to the top 4 of the hanger a spring clasp 9 comprising two jaws 10 and 11 provided with ears 12 through which extends a pin 13 forming a pivot for the jaws. A spring 14 carried by the pin 13

and with its ends bearing against the inner faces of the jaws 10 and 11 serves to keep the jaws normally in closed position; the jaw 10 may be secured to the frame in any suitable manner as by bending the end 15 about the top 4. It will be observed that the jaws may be opened to enable the hanger A to be attached to or detached from a support therefor by pressing the lower ends of the jaws toward each other, the jaws moving pivotally about the pin 13 and causing the upper ends to separate. While I prefer to employ the spring clasp or equivalent means for supporting the hanger, under some circumstances the clasp 15 may be omitted and the U-shaped upper end of the hanger engaged directly over a hook or peg when it is desired to suspend the same.

Slidably mounted upon the frame 1 is a clamping member 16 formed with eyes 17, 17 loosely encircling the sides 2 and 3, respectively, and adapted to be moved thereupon to any desired position so as to engage the snout 18 of the head H of the scarf S, the clamp 16 being adjustable along the sides 2 and 3 for different lengths of snouts. The clamp 16 is also preferably formed of a contour substantially similar to that of the snout so that its contact therewith will not mutilate or injure the latter and will also enable a snug engagement to be made therewith.

As is usual in scarfs of the character of those to which my invention relates, a tongue T is secured at its upper end to the under side of the snout by stitching or in any other suitable way, and is adapted to engage a catch or loop secured adjacent the tail end of the scarf when the latter is being worn. The tongue comprises, preferably, a metal plate with a fabric covering and is sufficiently resilient to permit the lower end thereof to be sprung slightly away from the head to enable the base 7 with the spool 8 to be slipped and retained thereunder when attaching the hanger to the scarf. The spool 8, being preferably 45 rotatable, enables the hanger to be slipped between the tongue and the head and withdrawn therefrom with facility and a minimum of frictional contact thereby obviating mutilation of the adjacent portions of the scarf.

Following the engagement of the base 7 and spool 8 beneath the tongue T, the clamp 16 is slipped downwardly upon the sides 2 and 3 lying on opposite sides of the tongue 55 against the under side of the head to engage over the snout and may be adjusted to securely grip the same irrespective of the length thereof, the conformation of the clamp 16 with the contour of the snout assisting in effecting a secure seating of the clamp thereon without abrasion of mutilation of the snout.

It will also be noted that because of the gradual divergence downwardly of the sides 60 65 2 and 3 the clamp, as it is pushed downwardly

thereon, effects a progressively tighter engagement between itself and the snout so as to securely attach the hanger to the scarf, the inherent resiliency of the wires 2 and 3, however, preventing such tight engagement 70 as would tend to mar or injure the snout.

The hanger when once attached to the scarf as just described may be left in position thereon as long as may be desired but may readily be removed when required by 75 merely slipping the clamp off the snout and unhooking the end of the hanger from beneath the tongue T. When in operative position the hanger is substantially incapable of relative movement with respect to the head or snout and the scarf may be handled or even tried on without removing the hanger therefrom.

In Figs. 1 and 2 I have shown a novel support B for a plurality of my improved 80 hangers with scarfs suspended therefrom. The support B may be preferably formed from a single piece of wire and comprises a hook or loop 20 adapted to be hung upon a rod or peg and a transverse section 21 formed with a plurality of spaced U-shaped depressions 22 within which the clasps 9 may be secured whereby the scarfs are maintained in definitely spaced relation and thus more effectively displayed for sale purposes. While 85 the removal of any hanger and its appended scarf, except perhaps the scarf disposed at the middle of the support, will tend to unbalance the support and cause its canting or tilting to some degree, the desirable spacing 90 of the remaining scarfs will still be maintained, the clasps 9 being retained within the depressions 22 and the scarfs hanging in substantially vertical, spaced, parallel relation.

While I have herein described with some 105 particularity one embodiment of my invention, it will be understood that I do not thereby desire or intend to limit myself thereto as it will be evident that various changes 110 may be made therein without departing from the spirit and scope of the invention as defined by the appended claims, the foregoing description and accompanying drawing being intended as illustrative only and not by way of limitation.

Having thus described my invention, I 115 claim and desire to protect by Letters Patent of the United States:

1. A hanger for a fur scarf comprising a frame and a clamp slidable along the sides 120 thereof and generally conforming between said sides to the profile of a transverse section through an animal's snout.

2. A hanger for a fur scarf comprising a wire frame of substantially trapezoidal shape 125 and severed transversely through the base to permit relative lateral yielding movement between its sides, and a clamp provided with eyes at its extremities respectively surrounding said sides and slidable thereon, the center 130

portion of the clamp between the eyes generally conforming to the profile of a transverse section through the snout of an animal and adapted to engage over the same.

- 5 3. A hanger for a fur scarf comprising a wire frame of substantially trapezoidal shape and severed transversely through the base to permit relative lateral yielding movement between its sides, a clamp provided with eyes at 10 its extremities respectively surrounding said sides and slidable thereon, the center portion of the clamp between the eyes generally conforming to the profile of a transverse section through the snout of an animal and 15 adapted to engage over the same, and a spring clasp secured to the apex of the frame for detachably suspending the latter from a support.

4. A hanger for a fur scarf having at one 20 end a stuffed animal head and provided beneath the snout thereof with a longitudinally extending tongue, said hanger comprising a frame having elongated sides and a transversely extending base adapted to engage beneath said tongue and a clamp slidable on 25 said sides and adapted to receive the snout of the animal head whereby the hanger is held in relatively fixed relation with the head of the scarf when operatively disposed thereon.

- 30 5. A hanger for a fur scarf having at one end a stuffed animal head provided on its under side with a longitudinally extending tongue, said hanger comprising longitudinally extending sides and a transversely extending base adapted to engage beneath the tongue, said sides when the base is so engaged lying adjacent the snout of the head, and a clamp slidable on said sides and engaged over said snout to hold the same in relatively fixed position with respect to said sides.

- 35 6. A hanger for a fur scarf having at one end a stuffed animal head and a longitudinally extending tongue disposed therebeneath, said hanger comprising a frame of wire the sides of which are adapted to lie adjacent the snout of the head, a transversely disposed base adapted to be engaged beneath the end of the tongue, and a clamp slidable on said sides and operable to engage over said snout to hold the same in relatively fixed relation with the sides with the apex of the frame projecting beyond the end of the snout.

- 40 7. A hanger for a fur scarf having at one end a stuffed animal head and a longitudinally extending tongue disposed therebeneath, said hanger comprising a frame of wire the sides of which are adapted to lie adjacent the snout of the head, a transversely disposed base 45 adapted to be engaged beneath the end of the tongue, a clamp slidable on said sides and operable to engage over said snout to hold the same in relatively fixed relation with the sides with the apex of the frame projecting beyond the end of the snout, and means adja-

cent the apex of the frame for detachably securing it to a support.

In witness whereof, I have hereunto set my hand this 27th day of June, 1929.

JULIUS H. HERRMANN.
